Inventor:

Geo. E. Stewart

UNITED STATES PATENT OFFICE.

GEORGE E. STEWART, OF COUNTY LINE, MICHIGAN.

GRAIN-TALLY.

SPECIFICATION forming part of Letters Patent No. 245,324, dated August 9, 1881.

Application filed January 29, 1881. (No model.)

To all whom it may concern:

Be it known that I, GEORGE E. STEWART, a citizen of the United States, residing at County Line, in the county of Genesee and State of Michigan, have invented a new and useful Improvement in Grain-Registering Machines, of which the following is a specification.

My invention relates to improvements in grain-registering machines so constructed that when the spout is opened to allow the grain to run out the measure is fastened in its place until the spout is again closed. The machine is also provided with devices by means of which a tally is made of the number of times the spout is opened and closed, thus showing a tally of the number of bushels of grain measured.

The object of my improvement is, first, to secure a tally of each measure of grain before removing it from the thrashing-machine; second, to prevent the waste or spilling of grain when being measured. I attain these objects by the mechanism illustrated in the accompanying drawings, in which—

Figure 1 is a side view of the entire machine with the spout closed, also representing by broken lines the position of arm, door, and curved rod when the spout is open. Fig. 2 is an end view with spout open; Fig. 3, an enlarged side view of cap detached, showing holes and figures on wheels, and the broken lines showing position of wheels.

Similar letters refer to similar parts throughout the several views.

The spout A, Fig. 1, is preferably made of iron, the ends being open. One end, at a, is attached, by hooks or otherwise, under the spout of the thrashing-machine. To one side of spout A are secured three stud-pins, s, which form axles for the tally-wheels G H I. To this side and the opposite side of spout A is secured one stud-pin each, t, to receive ends C of arms B B', the opposite ends of arms being bent on a radius of the length of arm. To this bent portion is riveted door D, extending from arm B to arm B', (see Fig. 2,) across end of spout, thus closing it. Arm B at end C, being bent at right angles, forms short arm e, to which is

pivoted pawl F. Pawl F engages with ratchet b on wheel G, and compels it to rotate when arms B B', carrying door D, are moved in one direction, but not when moved in the other, being prevented from so doing by spring m, also engaging with same ratchet, wheels G H I being registering-wheels provided on the side with figures from 1 to 0, Fig. 1. Over these figures is placed a cap, K, Fig. 4, having a hole, g, through it over each wheel large enough to allow only one figure on each wheel to be seen, as at 3 6 9, Fig. 4. On the outer side, and to the center of door D, (see Fig. 2,) is secured a curved rod, L, Fig. 1.

In operating this machine wheels G H I are placed on stud-pins with cipher under hole g in cap K. The door D being raised the spout A thereby is closed. Place the measure (not here shown) to receive the grain at end of spout, under rod L, push the door down, opening the spout. The free end of rod L enters in the measure, thereby preventing it from being removed until door D is raised. Raising door D vibrates arms B e, carrying pawl F, which engages with ratchet b and moves wheel G one-tenth of one revolution, thus bringing figure 1 in view. With the tenth movement of door spur e engages with gear l in wheel H, turning it one-tenth of one revolution. When wheel H makes the tenth move its spur e engages with gearing l on wheel I, moving it one-tenth, thus bringing the different figures in view at hole g in cap, showing a tally, as at 3 6 9, Fig. 4. Thus by the movement of the door a tally is made.

What I claim as my invention, and desire to secure by Letters Patent, is—

1. In a grain-registering machine, the combination of arms B and e, pawl F, door D, and rod L, all substantially as shown, for the purpose specified.

2. In a grain-registering machine, the combination, with the spout A, of the door D and rod L, substantially as described.

GEO. E. STEWART.
